The ornamental design for a sole plate for an article of footwear, as shown and described.

DESCRIPTION

FIG. 1 is a lateral side view in perspective of a sole plate for an article of footwear showing my new design;

FIG. 2 is a medial side view of the sole plate of FIG. 1;

FIG. 3 is a lateral side view of the sole plate of FIG. 1;

FIG. 4 is a top view of the sole plate of FIG. 1;

FIG. 5 is a bottom view of the sole plate of FIG. 1;

FIG. 6 is a rear view of the sole plate of FIG. 1;

FIG. 7 is a front view of the sole plate of FIG. 1; and,

FIG. 8 is a front view of the sole plate of FIG. 1 in partial cross-section taken along line 8-8 of FIG. 5.

FIGS. 1-8 illustrate a right-footed sole plate for a right-footed article of footwear. A second embodiment is the corresponding figures for a left-footed sole plate (for a left-footed article of footwear), which are mirror images of the views depicting the right-footed sole plate. Accordingly, the figures pertaining to the left-footed sole plate have been omitted.

The broken line illustration of environmental structure in the drawings is not part of the claimed design.
